MANHOLE FRAME AND COVER

Daniel C. Mulvihill, Hannibal, Mo., assignor to
 Hannibal Car Wheel & Foundry Company,
 Hannibal, Mo., a corporation of Missouri

Application January 7, 1932. Serial No. 585,227

5 Claims. (CL. 94—35)

This invention relates to a closure and a frame therefor, adapted to be used on a man-hole, cistern or the like; and the principal object of the invention is to provide a cover that can be removed or placed in position with great ease and that will remain firmly seated and securely locked upon the frame when it has once been placed thereupon.

Further objects and advantages of the invention will be revealed as the disclosure is read in connection with the accompanying drawing, illustrating a preferred embodiment of the invention, in which

Fig. 1 is a plan view of the cover in place on the frame;

Fig. 2 is a vertical section taken on line 2—2 of Fig. 1;

Fig. 3 is a vertical section taken on line 3—3 of Fig. 1;

Fig. 4 is a plan view of the frame;

Fig. 5 is a plan view of the reverse side of the cover; and

Fig. 6 is a fragmentary sectional view taken on line 6—6 of Fig. 4.

It will be understood that the gist of the invention can be embodied in other forms than that disclosed herein, which should fall within the scope of the claims.

The frame 10 is surrounded by the concrete masonry or other material 11 of which the walls of the man-hole or pit are constructed. In its general form the frame resembles an angle ring; it has a cylindrical body portion 12, equipped with an outwardly-disposed flange 13 around its lower edge, imbedded in the material of the wall 11.

Extending around the inside of the cylindrical body portion 12 is the interior flange 14, along the upper surface of which adjacent the body portion 12 is a groove 15. In order that the top 40 16 of the cover 17 may be flush with the top edge of the frame and wall when the cover rests upon the interior flange 14, the distance from the top surface of the interior flange to the top edge 18 of the frame is made equal to the thickness of the cover.

In the construction shown there are two gaps 19 in the interior flange 14, but the number of such gaps may be varied, as will be seen. Flush 50 with each gap on one side thereof is a lug or stop 20 projecting from the lower side of the interior flange. There is also a wedge-shaped projection 21 on the lower side of the flange, adjacent each gap and on the opposite side of the gap from the stop. Immediately above each gap is a rounded

notch 22 in the inside of the top edge of the frame 10, having the same width as the gap.

The cover 17 which has the shape of a frustum of a cone has its seat upon the interior flange 14 and has studs 31 on its upper surface, which will provide good traction when the cover and frame are used for a street man-hole. The diameter of the circular upper surface 16 of the cover, which, because of the above described shape of the cover, is greater than the diameter of the lower surface 30 of the cover, is only slightly less than the interior diameter of the cylindrical body portion 12 of the frame, so that the cover 17 is rather closely fitting at the top. Extending from the lower surface of the cover 17 near its periphery are the lugs 23, at points whose positions correspond to the positions of the gaps in the interior flange of the frame. Each of these lugs has a radially-extending tooth 24, the width of which is slightly less than the width of the gaps.

Passing through the cover 17 is a radially-inclined passage 25 which, in the embodiment illustrated, enters the cover near its outer edge. The passage 25 may be surrounded on the lower side of the cover by the boss 26 of triangular longitudinal section, and on the upper side of the cover by a slightly raised boss 27. Thus the cover will be reinforced at the passage 25, which is adapted to receive a suitable bar 28 to be used as a lever for rotating the cover on its seat. As explained below, it is convenient for the bar 28 to be tapered at one end. In the top portion of the outer edge of the cover immediately opposite the inclined passage 25 may be provided a rounded notch 29 of the same width as the rounded notches 22 in the frame.

When the cover is to be placed in position on the frame it is pulled on to the frame in such a manner that one of the lugs 23 is brought into a notch 22, whence the cover lug will slide down through the gap 19 which is below said rounded notch. It will be noted that the rounded notches 22 facilitate the placing of the cover in the proper position for it to settle in place upon the interior flange 14. After one cover lug is in position in the corresponding gap of the interior flange it will be an easy matter to shift the cover so that the remaining lugs enter their corresponding gaps and the cover settles in place. The cover may also be simply held centered above the frame, turned until the cover notch 29 is opposite one of the frame notches 22, and then allowed to settle in place upon the interior flange.

The pointed bar 28 may now be inserted in the passage of the cover and used as a lever to rotate

the cover slightly in a clock-wise direction to the position shown in Figs. 1, 2 and 3. The teeth 24 of the lugs 23 will now be wedged against the sloping lower surface of the projections 21 on the 5 interior flange.

Because the cover has now been securely locked upon the frame it will be impossible to remove it without the use of the pointed rod 28. Hence it will not be possible for anyone to remove the 10 cover but an authorized workman who carries the proper tool. A cover of the construction described will be less likely to be left off, because the workman will not leave the cover for someone else to replace when he knows that if he 15 carries away the tool the cover can not be rotated into locked position after it has been placed on the seat.

The fact that there are as many positions in which the cover may be placed upon the frame 20 as there are lugs on the lower surface of the cover contributes to the ease with which the cover may be placed. Because of the notch which has been provided in the upper surface of the cover and the similar notches in the frame it is possible to tell by a glance at the cover whether it is in 25 locked or unlocked position, or whether it has been turned far enough to unlock it when it is being removed.

Moreover when the workman wishes to remove 30 the cover he will find it a useful expedient to place the point of his tool in the rounded notch 29 of the cover and give the cover a few taps in a counter-clockwise direction to loosen it. Thus the notches provided in the cover and frame facilitate the removal as well as the placement 35 of the cover.

After the cover has been loosened slightly the pointed bar 28 is of course inserted in the passage and used to rotate the cover in a counter-clockwise direction until the teeth 24 of the cover lugs come in contact with the stops 20 on the interior flange. To assist in the removal of the 40 cover one side can then be easily lifted off the interior flange by pressing down or raising up on the end of the pointed bar. The pointed end of the bar 28 is to allow more ready insertion into 45 the passage.

The construction described insures ease of removal of the cover without sticking. Even 50 though the iron of the frame or cover may become distorted or foreign matter may become lodged between the frame and the outer edge of the cover, the cover will not stick while it is being turned on its seat because the above described shape of the cover provides for its periphery to approach close to the inner surface of the frame only at the very top. The groove 55 in the upper surface of the interior flange is also of value for providing clearance space between the cover and the inner surface of the frame.

After being locked in place the cover is held firmly to its seat at as many points as there are lugs provided on its lower surface. When the 60 cover is used on a street man-hole the familiar clanking sound will not be produced when a vehicle passes over it. Any foreign matter which may fall between the frame and the edge of the cover will settle into the groove 15 and will not have the tendency to work under the seat of the cover which it would have if the groove were not provided. At any time the cover is removed, in 65 case much dirt is found to have accumulated in the groove the point of the bar 28 may be used to clean it out. Since the upper surface of the interior flange is in the form of a raised seat, with

provision for foreign matter to fall either off the inner edge of the flange or off the other side of the seat into the groove, it is apparent that dirt may be brushed off the cover seat with especial ease to provide a smooth and true surface on which the cover may rest. Furthermore any dirt which remains upon the seat will tend to be pushed off or ground off when the cover is being placed and locked. The presence of pebbles or dirt on the seat of the man-hole cover will of course prevent a steady and firm seating of the cover.

A few of the features which give simplicity, lightness and strength to the construction may be noted. The interior flange 14 not only serves as a seat for the cover, but also, by virtue of the projections on its lower side, provides means to cooperate with the teeth on the cover lugs to allow the cover to be locked in position. The side of each lug opposite the tooth is made sloping and the lugs themselves are of the lightest construction consistent with the amount of strength that is required of them. The boss 26 on the lower side of the cover serves to strengthen the same against the action of the pointed bar 28 when it is being used as a lever and is conveniently made an integral extension of one of the cover lugs 23.

I claim as my invention:

1. A man-hole frame and cover, the frame having an inwardly-projecting flange interrupted by a plurality of gaps at equal intervals, and the cover being adapted to be supported on the flange, provided with a radially-inclined passage, and supplied with lugs on its lower side at points whose positions correspond to the positions of the gaps in the flange, each of which is equipped with a radially-extending tooth, the teeth being adapted to co-operate with the flange to prevent the cover from being removed after it has been placed in position on the flange and rotated slightly, unless it is first rotated back into its original position.

2. In a man-hole construction, a frame having a cylindrical body portion and a non-continuous, inwardly-extending flange, with a groove along its upper surface adjacent the body portion, a cover in the shape of a frustum of a cone adapted to be supported on the flange, having projections on its lower side near its periphery adapted to engage the lower side of the flange when the cover is rotated slightly, a notch in the upper edge of the periphery of the cover above one of said projections, notches in the upper edge of the frame in such positions that they lie opposite said projections when the cover has been placed upon the flange but not rotated, and means on the cover engageable by a bar for turning the cover on its seat.

3. In a man-hole construction, a frame carrying cover-supporting means, interrupted by gaps at regular intervals, provided with a stop flush with each gap, and having a wedge-shaped projection on its lower side adjacent each gap and on the side of the gap opposite said stop, and a cover adapted to be supported on said means, having an outwardly-inclined passage therethrough, and having a plurality of lugs on its lower side in positions corresponding to the positions of the gaps in said means, each of which is equipped with a tooth adapted to be wedged against the lower surface of one of the wedge-shaped projections on said means when the cover is placed thereupon and rotated slightly.

4. A frame and cover for a man-hole aperture, said frame having wedge means and having

an inwardly-disposed flange surrounded by an upstanding rim, with a portion rabbeted out along and adjacent to the junction between the rim and the upper surface of the flange, said 5 rim having a substantially cylindrical inner surface perpendicular to the flange and a cover substantially in the shape of a frustum of a cone, adapted to be supported wholly upon the flange, and having means on its inner side to secure it 10 in place by wedging against said wedge means when it is rotated slightly from an unlocked position on the flange.

5. A structure for a man-hole including a frame having an inwardly disposed flange 15 rounded by an upstanding rim having its inner

surface substantially cylindrical and perpendicular to the flange, and a cover adapted to be supported wholly on the flange having means on its inner side for securing it in place when it is rotated from an unlocked position on the flange, 80 having the diameter of its exposed surface only slightly less than the interior diameter of said rim, so that there is close lateral approach to said rim at that part of the peripheral edge of the cover that is adjacent its exposed surface, and having the remainder of its peripheral edge receding inwardly a substantial distance from said rim to give clearance between said rim and the inner parts of said peripheral edge. 85
